CLOSURE

Leslie R. N. Carvalho, Toledo, Ohio, assignor to
Owens-Illinois Glass Company, a corporation
of Ohio

Application June 1, 1936, Serial No. 82,812

1 Claim. (Cl. 215—95)

The present invention relates to improvements in bottle closures and more particularly to a slip-over type for sealing a bottle or other container.

5 An object of the invention is the provision of a closure adapted for frictional holding engagement with the smooth outer surface of the neck of a bottle whereby the cap may be removed or replaced with a minimum of effort and motion.

10 Another object of the invention is the provision of a novel seal for a bottle, which is adapted to replace the use of long corks and stoppers such as are now generally employed in sealing 15 certain types of containers, namely wine and liquor bottles.

Another object of the invention is the provision of a tamper-proof outer seal for holding a closure of the above character against unauthorized removal from the container.

20 Other objects will be in part apparent and in part pointed out hereinafter.

In the drawing:

Fig. 1 is a vertical sectional view of my invention shown applied to a bottle neck;

Fig. 2 is a similar view of the closure applied to a different type of bottle finish;

Fig. 3 is an elevational view of a bottle showing a closure and sealing band applied thereto;

30 Fig. 4 is an elevational view of the closure applied to a bottle, the sealing band having been removed;

Fig. 5 is a horizontal sectional view taken on line 5—5 on Fig. 3; and

35 Fig. 6 is a fragmentary sectional view illustrating the closure before being applied to a bottle.

Referring to Fig. 1 of the drawing the invention is shown in combination with a bottle 40 5 having a reduced neck portion 6 defining a filling and discharging opening 7. The neck portion 6 is provided at its outer end with an axial annular surface 8 tapering slightly toward the outer end of the neck to provide a smooth side 45 sealing surface free of any indentations or projections, to which a closure 9 is applied.

The closure 9 forming the subject matter of the present invention comprises a shell having a circular top portion 10 and a depending marginal attaching flange 11 or skirt formed thereon. A sealing liner 12 disposed within the top 50 55 of the shell may be formed of a disk of cork or other suitable material which preferably is covered with a thin sheet of acid resisting metal foil 13, as a protection for the contents of the

container and to form a top seal therefor. The flange 11 provides support for a sealing ring 14 or band which is preferably rectangular in cross-section and formed of cork or a suitable composition which is adapted to provide frictional holding engagement with the bottle neck. The ring 14 is preferably formed from a continuous strip or cut from a sheet of material and in this form can more readily be treated with paraffin. The lower edge of the flange 11 is rolled 10 inwardly at 15 beneath the ring and thereby securely holds the shell, liner and sealing ring assembled.

It will be noted that only a slight compression of the ring 14 is necessary to provide a 15 satisfactory seal, thereby permitting relatively easy application and removal of the cap. Fig. 6 illustrates the closure prior to its application to the container and shows the cork ring 14 before being compressed. The omission of the usual 20 screw threads from the bottle neck provides a plain exterior surface to receive the flange of the cap, thereby eliminating entirely the objections as to speed of application and removal such as is encountered in the use of screw caps. When 25 the cap is applied to a bottle as shown in Figs. 1, 2 and 6 the liner 12 is pressed into contact with the sealing surface at the open end of the neck and provides a top seal for the container 30 which is maintained by the frictional engagement of the ring 14 with the surface 8. By extending the liner 12 into contact with the flange 11 the margin thereof is concealed by the ring 14 and the liner is held in position. The treated edge of the band 14 when pressed against the resilient surface of the liner provides a seal 35 and prevents the contents of the container from coming in contact with the metal cap. The combination of the sealing liner 12 and the ring 14 provides a doubly secure seal for the container 40 and contents.

When the closure 9 is originally applied to a filled container it is held against accidental or unauthorized removal by a sealing band 16 which encircles the cap and a portion of the neck 6 of 45 the bottle. The band 16 has its upper margin spun inwardly over the edge of the cap to form a retaining rim 17 or flange and extends downwardly to enclose and engage an annular rib 18 formed on the bottle neck, the diameter of the rib 50 and cap being substantially equal. The rib 19 forms a downwardly facing shoulder 19 under which the lower margin of the band is turned, thereby completely enclosing the cap and rib and holding the cap against any movement that will 55

tend to loosen it while being transported. The band 16 is scored at 20 to provide a conventional tear strip 21 for removing the band.

Fig. 2 illustrates a type of container having a 5 relatively long neck portion such as, for instance, a wine bottle, wherein the band 16 is of increased width to present a more pleasing appearance than would the narrower band shown in Fig. 1, and further to more nearly simulate the appearance 10 of the foil or cellulose caps now generally in use on such containers. Fig. 4 shows the closure 9 applied to a similar type of container from which the sealing band has been removed. Thus an effective reseal is provided.

15 Figs. 3 and 5 illustrate a type of sealing band 22 which is entirely removable from the container on destroying the seal and is formed from a strip of relatively thin sheet metal. A tab 23 or finger piece is provided on one end 24 of the 20 strip and is connected thereto by a relatively narrow neck 25. The reduced width of the neck 25 adjacent the tab 23 forms a shoulder 26 on the tab, the purpose of which will become apparent 25 presently. The opposite end 27 of the band 22 is provided with a transverse slot 28 having longitudinally tapered end walls 29. The greatest 30 width of the slot 28 is sufficient to permit the passage of the tab 23 therethrough, the end walls 29 tapering to substantially the width of the neck 35 25. The side wall 30 of the slot adjacent the end 27 of the strip is provided with score lines 31 or weakened portions to permit tearing when it is desired to destroy the seal to open the container. The ends of the band are connected previously 40 to applying it to a bottle by passing the tab 23 through the wide portion of the slot 28 until the band can be expanded and the shoulder 26 and neck 25 drawn into engagement with the narrow end of the slot until the shoulders 26 overlie the tapered end walls 29, thereby preventing withdrawal of the tab 23. The diameter of the band when expanded is substantially equal to that of the cap, thus necessitating destruction of the wall 30 to remove the band.

45 The upper margin 32 of the band is turned radially inward over the margin of the cap in the manner shown in Figs. 1 and 2, previous to its application to the cap, and the lower margin 33 is then spun under the bead 18, thereby preventing unauthorized and undetectable removal 50 of the band.

Removal of the band is accomplished by grasping the tab 23 and pulling radially outward and in the direction of the scored wall 30, whereby the member will tear along one or both of the lines 31 and preclude any further use of the band. The band may then be expanded and removed from the bottle, leaving the cap in sealing engagement with the bottle neck.

Application of the present closure to bottles of 10 the above character and particularly those formerly employing corks or stoppers of extra length eliminates substantially all the confusion and effort now required to open them. The adhering quality of the cork ring 14 to the surface of the 15 glass, when the closure is applied, prevents accidental removal of the closure, which at the same time is not sufficient to prevent easy manual removal thereof. It will be observed that the entire closure presents a greater exposed gripping and 20 sealing surface than is present in any ordinary type of stopper.

Modifications may be resorted to within the spirit and scope of the appended claim.

I claim:

The combination with a bottle having a reduced neck formed with an external bead encircling the same, the outer peripheral surface of said neck above said bead being free of external indentations or projections and tapering upwardly and inwardly, of a slip-on closure telescoped over said neck above said bead and comprising a circular disk-like top, an annular flange depending from the margin of said top, a resilient sealing disk disposed within said closure, said disk engaging the top and having a diameter substantially equal to the diameter of the same, a metal foil liner underlying said disk and concealing the same, a resilient sealing ring disposed within said closure in snug engagement with the inner surface of said flange and, together with the sealing disk, gripping the marginal portions of the foil liner, and a circular ring-like band having its upper edge beaded over the peripheral margin of said top and exposing the central region thereof and having its lower edge beaded underneath said annular bead to maintain said closure in telescoped position on said bottle neck.
